UNITED STATES PATENT OFFICE.

CHARLES FREDERIC DUFUAUX, OF GENEVA, SWITZERLAND.

PERMANENT MAGNET FOR ELECTRIC MACHINES.

Application filed August 23, 1921. Serial No. 494,487.

To all whom it may concern:

Be it known that I, CHARLES FREDERIC DUFUAUX, a citizen of the Republic of Switzerland, residing at Geneva, Switzerland, have invented certain new and useful Improvements in Permanent Magnets for Electric Machines, of which the following is a specification.

During a long time permanent horse-shoe magnets have been employed with magneto-electric machines. These magnets have two inconvenient factors: First of all, if it is desired to have the air-gap of the magneto-armature to remain constant, it is necessary to provide the electro-magnet with polar pieces, which render it heavier and complicate its construction. Furthermore, if the magnet is to be placed inside a cylindrical casing, this cannot be done without the loss of much space and the use of complicated devices for fixing it properly in position.

To obviate these inconveniences, already some years ago the construction of permanent bell-magnets has been devised. These have the shape of a sleeve, slit according to two or several of its generatrices, in order to separate the poles. The right section of the magnets being circular, it is not necessary to provide the latter with polar pieces, and they can be very easily fixed inside a cylindrical casing, however, their construction is delicate and expensive. It is, in fact, necessary to make a sleeve of steel, which means complicated work, and to make longitudinal fissures in said sleeve, requiring also a long and difficult working process.

The magnet which is the object of this invention has, with respect to the horse-shoe magnets, the same advantages as the bell-magnets, and is easier to be manufactured than the latter type.

The drawing represents a descriptive, but not restrictive example of a magneto for lighting purposes, adapted to be fixed on to a bicycle, its inductor comprising two identical forms of the magnet, given by way of example only, which comprises the object of this invention.

Fig. 1 represents an axial section of the magneto. Fig. 2 shows one of the magnets with the spring holding it firm in position

in the magneto. Fig. 3 represents a detail. Fig. 4 shows a perspective view of the magnets.

55

The represented magneto comprises a casing, constructed with a cylindrical jacket a^3 and two flanges a^1 and a^2 . The armature b can rotate freely in said casing. The shaft of the armature extends through the flange a^2 and carries outside the latter a pulley c . This pulley has to come in contact with the pneumatic tire of the front wheel of the bicycle, so as to actuate the rotor b at the same time as said front wheel rotates. The other extremity d^2 of the shaft of the rotor revolves inside a hollow cylinder, conductor, insulated from the bottom a^1 through which it passes, and whereon a terminal d^3 of the machine is fixed.

70

The armature of the magneto consists in the two permanent magnets e ; each one of these is constructed of a steel plate, in the middle of which is made a rectilinear fissure e^1 for the purpose of separating the poles, and which plate is afterwards bent, in such a way as to form, in a right section, the form of an arc of a circle of about 180° (see Fig. 2, bottom). The flange a^1 has a shoulder f^1 against which comes to butt the inferior extremity of the two magnets e ; the superior extremity of these magnets presses against an annular projecting piece f made in the flange a^2 . An elastic, slit ring h (see Figs. 1 and 3) fixed inside the magnets, holds the latter in position, as well as the two springs g (see Figs. 1 and 2), the middle part of which presses against the walls of the slit e^1 , whilst the extremities press against the jacket a^3 . k is a support, represented in a scheme, permitting the fixing of the magneto to the frame of the bicycle.

90

The magnet can be very easily manufactured, since it suffices to make a fissure e^1 in a steel plate, and afterwards to bend the latter according to a half-cylinder. It is not necessary to provide said magnet with polar pieces in order to create a constant air-gap of the rotor. It is also most easy to fix the two magnets inside the cylindrical casing, solely by means of a shoulder f^1 of one of the flanges, of a projecting piece f on the other flange, and of the three

100

elastic pieces *h* and *g*. The two magnets can be very easily taken off and replaced in position.

Having thus fully described the invention, what is claimed as new and desired to be secured by Letters Patent is:

A permanent magnet for electric machines, characterized by the fact that it is

composed of at least one steel-plate bent according to a cylindrical surface embracing an angle of at least 180° , and provided, at one of its extremities, with a slit separating both poles. 10

In testimony whereof I have affixed my signature.

CHARLES FREDERIC DUFaux.
